UNITED STATES PATENT OFFICE.

CARL K. FREDERICK, OF DETROIT, MICHIGAN.

COAL-CAR GUARD.

1,221,434.

Specification of Letters Patent.

Patented Apr. 3, 1917.

Application filed October 16, 1916. Serial No. 125,816.

To all whom it may concern:

Be it known that I, CARL K. FREDERICK, a citizen of the United States of America, residing at Detroit, in the county of Wayne 5 and State of Michigan, have invented certain new and useful Improvements in Coal-Car Guards, of which the following is a specification, reference being had therein to the accompanying drawings.

10 This invention relates to coal car guards, and my invention aims to furnish a coal car body with strong and durable guards that can be easily and quickly placed in a position to cover and screen the top of a car 15 filled with coal or other merchandise, the guards being arranged to assume positions in parallelism with the outer sides of the car walls, so as not to interfere with the usual filling or loading of the coal car.

20 Large quantities of coal are lost by persons surreptitiously removing coal from the top of coal cars while in transit. Small boys with poles will often pry loose lumps from the edge of the car and unscrupulous 25 men will board cars and throw off such coal as is loose and convenient to handle. To prevent this nefarious practice, I have devised novel guards that can be easily manipulated and used in connection with cars 30 of various kinds.

The matter entering into my invention will be hereinafter described and then claimed, and reference will now be had to the drawings, wherein—

35 Figure 1 is a side elevation of a coal car provided with guards in accordance with my invention;

Fig. 2 is an end view of the car showing the guards in an operative position;

40 Fig. 3 is a similar view of the car, partly broken away and partly in section, showing the manner of placing the guards in operative position;

Fig. 4 is a detailed view of a portion of 45 the end guard, and

Fig. 5 is an enlarged cross sectional view of a portion of the manipulating mechanism.

In the drawing, there is shown a car body having longitudinal parallel side walls 1 and end walls 2, said end walls having upper inclined edges 3 constituting end supports. It is preferable to have the edges 3 inclined downwardly from a point central of the upper edge of each wall to the side

walls 1, as shown in either of the end views, 55 Figs. 2 and 3. At the juncture of the end walls 2 and the side walls 1, there are vertical angle bars 4 coöperating with said walls 1 in providing open channels or guides for the ends of foraminous guards 5. 60 The foraminous guards 5 are preferably in the form of rectangular frames supporting a strong and durable wire fabric or metallic screen. These frames are adapted to slide in the end guides and rest upon yieldable 65 seats 6 provided therefor in the lower ends of said guards.

Journalized in the end walls 2, contiguous to the upper ends of the angle bars 4, are the ends of longitudinal shafts 7 and attached to said shafts and adapted to wind and unwind thereon are chains or cables 8. These chains or cables 8 are attached to the lower edge of each guard and by rotating the shafts 7 the guards 5 may be raised 70 above the upper edges of the walls 1, said guards having shoes or rollers 9 to ride against the angle bars 4 as the guards are raised.

To operate the shafts 7, the outer sides of 80 the end walls 2 are provided with hoisting and brake mechanism. On the ends of the shafts 7 are small gear wheels 10 meshing with gear wheels 11 mounted upon rotatable stud shafts 12 journaled in the end walls 2 85 and brackets 13 carried thereby. Mounted upon the shafts 12 are large gear wheels 14 and brake wheels 15. The large gear wheels 14 mesh with small gear wheels 16 mounted upon shafts 17, journaled in the 90 end walls 2 and the brackets 13. The shafts 17 are adapted to be rotated by suitable cranks or handles placed on the outer rectangular ends thereof and gravity pawls 18 are adapted to hold the shafts 17 against 95 accidental rotation. Associated with the brake wheels 15 are brake bands 19 and levers 20, these elements controlling the rotation of the shafts 17 when the pawls 18 are thrown out of engagement with the small 100 gear wheels 16.

Pivots connected to the ends of the guards 5, at the upper edge thereof, are end arms composed of rods 21 and tubular members 22, said rods extending into the tubular members 22 and connected thereto by coiled springs 23 encircling the inner ends of the rods 21, so that the rods 21 may

yield relative to the tubular members 22. The tubular members 22 have the lower ends thereof pivotally connected to blocks 24 slideable in vertically disposed channel guides 25 on the outer sides of the end walls 2. These channel guides have the lower ends thereof provided with yieldable seats 26 for the blocks 24. The blocks 24 are connected to chains or cables 27 trained over 10 sheaves or pulleys 28 adjacent the upper edges of the walls 2, and said chains or cables extend downwardly and are attached to and wound upon drums 29 supported by brackets 30, carried by the end walls 2. The drums 29 have large gear wheels 31 meshing with small gear wheels 32 on shafts 33 journaled in the brackets 30 and said shafts will accommodate handles or cranks by which movement may be imparted to the 15 drums 29. Gravity pawls 34 are adapted to prevent accidental rotation of the shafts 33.

In Fig. 2, the guards 5 are shown in an active position, covering or closing the top 25 of the car body by resting upon the inclined edges 3 of the end walls 2. In this position of the guards 5, the end arms are in parallelism, and when it is desired to restore the guards 5 to an inactive position in parallelism with the side walls 1 of the car, the drums 29 are rotated to wind the chains or cables 27 thereon and elevate the blocks 24 in the channel guides 25. As the blocks 24 are raised, the upper edges of the guards 5 are shifted upwardly by the end arms to the 30 position shown in Fig. 3. By holding the shafts 7 against rotation through the medium of the brake band 19 and the levers 20, the pawls 18 can be thrown out and the 35 shafts 7 allowed to gradually rotate and lower the guards 5 in the angle bars 4, said guards descending by gravity. During these operations the springs 23 of the end arms will compensate for any inequalities between 40 the positions of the upper ends of the guards and the blocks 24, besides serving as cushioning springs when the guards are lowered on to the upper edges of the walls 2.

From the foregoing, it will be observed 50 that I have devised hoisting devices for raising the guards over the side walls of the car body and other hoisting devices for lowering the guards into operative position and assisting in restoring said guards to an inactive position, all of said devices being manually actuated and easily controlled.

While in the drawings there is illustrated a preferred embodiment of my invention, it is to be understood that the structural elements are susceptible to such variations and modifications as fall within the scope of the appended claims.

What I claim is:

1. The combination with a car body, of 65 foraminous guards arranged in parallelism

with the side walls of the car body and adapted to be raised to cover the top of said car body, means connected to the lower edges of said guards adapted to raise the guards, and means connected to the ends of the 70 guards at the upper edges thereof adapted to control lowering of said guards.

2. The combination with a car body, of foraminous guards arranged in parallelism with the side walls of said car body, and 75 adapted to be raised to rest upon the end walls of said car body and provide a cover for the top of said car body, means connected to the lower ends of said guards adapted for raising and lowering said 80 guards, and end arms connected to the ends of said guards at the upper edges thereof adapted for controlling the raising and lowering of said guards.

3. The combination with a car body having 85 side walls and end walls, of guards in parallelism with the outer sides of said side walls and adapted to be raised and lowered on to said end walls to provide a cover for said car body, means operable on the end 90 walls of the car body and attached to the lower edges of said guards for raising said guards, and hoisting devices on the end walls of said car body and having connection with the ends of said guards at the upper edges 95 thereof adapted for controlling the movement of the upper edges of said guards.

4. The combination with a car body having side walls and end walls, of guides at the ends of the side walls of said car body, 100 guards slideable in said guides normally in parallelism with the side walls of said car body, arms attached to said guards at the ends thereof, means on the end walls of said car body for raising and lowering the lower 105 edges of said guards, and means on the end walls of said car body for raising and lowering said arms.

5. The combination with a car body having side walls and end walls, of vertical 110 guides at the ends of said side walls, foraminous guards slideable in said guides and normally in parallelism with the side walls of said car body, hoisting devices on the end walls of said car body adapted for raising 115 and lowering the lower edges of said guards, guides on the end walls of said car body, blocks slideable in said guides, arms connecting said blocks and the ends of said guards at the upper edges thereof, and means on 120 the end walls of said car body for raising and lowering said blocks.

6. The combination with a car body having side walls and end walls, of shiftable 125 guards normally in parallelism with the outer sides of the side walls of said car body and adapted to be raised and lowered on to the end walls of said car body to provide a cover therefor, arms at the end walls of said car body adapted for raising said guards 130

off of the end walls of said car body to permit of said guards lowering by gravity into parallelism with the side walls of said car body, and means attached to the lower edges 5 of said guards and operable at the end walls of said car body for controlling the lowering movement of said guards.

In testimony whereof I affix my signature in the presence of two witnesses.

CARL K. FREDERICK.
